IGNITION APPARATUS

Max G. Bales, Anderson, Ind., assignor to General Motors Corporation, Detroit, Mich., a corporation of Delaware

Application September 11, 1951, Serial No. 245,990

8 Claims. (Cl. 200—19)

The present invention relates to distributor equipment and is particularly directed to the provision of improved mounting of the circuit breaker mounting plate.

An object of the present invention is to provide means by which the circuit breaker mounting plate for the circuit breaker of the distributor may be mounted for oscillatory movement to permit of accurately advancing and retarding of the ignition of internal combustion engines without plate wobble, plate jamming or horizontal misalignment and minimum friction. This object is accomplished by a housing member and a circuit breaker mounting plate member positioned within the housing on a plurality of bearings and immovably positioned within the housing.

Another object of the invention is to provide a plurality of anti-friction bearing members for supporting the circuit breaker mounting plate. This is accomplished by bearing members immovably retained in a fixed position by the housing and adapted to be engaged by ears associated with the circuit breaker mounting plate.

In carrying out the above objects it is a further object to provide relative curvatures between the shoes and the bearing member by which the shoes may be controlled to yield to provide point contact, or line contact, or full surface contact to control shifting due to wear and reduce turning friction.

Another object of this invention is to provide an improved distributor assembly comprising two members rotatable with respect to one another which members consist of a distributor housing and a circuit breaker plate mounted therein and adapted to be oscillated by an engine controlling vacuum control, one of said members having a plurality of antifriction bearing elements attached thereto and the other of said members including a bearing groove adapted to at least partially fit around said bearing elements whereby the breaker plate is freely rotatable with respect to the housing without wobble or binding.

In carrying out the above object it is a further object, in some cases, to position the bearing elements on the distributor body wall and to form the groove in a plurality of spaced ears or shoes carried by the breaker plate.

A still further object is to provide at least one spring shoe to permit easy assembly and to provide stop means effective when the assembly is complete to prevent accidental displacement of the plate. In carrying out the above object the stop means may take the form of a member removably carried by the circuit breaker plate or the stop means may be a shoulder in the distributor body member.

Further objects and advantages of the present invention will be apparent from the following description, reference being had to the accompanying drawings wherein a preferred embodiment of the present invention is clearly shown.

In the drawings:

Fig. 1 is a plan view of an ignition timer with the distributor cap removed.

Fig. 2 is a sectional view taken on line 2—2 of Fig. 1.

2

Fig. 3 is a fragmentary plan view, on an enlarged scale, taken on line 3—3 of Fig. 2.

Fig. 4 is a sectional view taken on line 4—4 of Fig. 3.

Fig. 5 is a view looking in the direction of arrow 5 in Fig. 4.

Fig. 6 is a front view of the bearing member.

Fig. 7 is a sectional view taken on line 7—7 of Fig. 4.

Fig. 8 is a view similar to Fig. 2 but showing a modification of the invention.

Fig. 9 is a sectional view taken on line 9—9 of Fig. 8.

Fig. 10 is a fragmentary sectional view showing a slightly modified form of bearing structure of a bearing and mounting member shown in Fig. 8.

Fig. 11 is a sectional view taken on line 11—11 of Fig. 10.

Fig. 12 is a sectional view similar to Fig. 8 showing another modification of the invention.

Fig. 13 is a view similar to Fig. 8 but showing another modification of the invention using metallic anti-friction bearing staked to the housing.

Fig. 14 is a sectional view taken on line 14—14 of Fig. 13.

Fig. 15 is a view similar to Fig. 8 but showing still another modification of our invention.

Fig. 16 is a sectional view taken on line 16—16 of Fig. 15.

Fig. 17 is a fragmentary sectional view showing a modification in the mounting plate for the bearing member shown in Fig. 15.

Fig. 18 is a sectional view taken on line 18—18 of Fig. 17.

Referring to the drawings, a timer housing 20 is counterbored at its open end to provide a cylindrical wall 21 and a shoulder 22. The cylindrical wall 21 is provided with circumferentially spaced radial openings 23, 24 and 25, in the form of an isosceles triangle, the angle between center of the openings 24 and 25 being substantially 130° and the angle between opening 24 and opening 25 being 100°. It is to be understood that the angles specified could be changed so to form a triangle with unequal or equal sides. The housing rotatably supports an engine driven shaft 26 in the conventional manner and drives a timer cam 27 having lobes 28. The lobes of the cam engage a rubbing block 29 carried by a lever 30 pivoted on a post 31 attached to a circuit breaker mounting plate 32. Adjustably mounted on the plate 32 is a bracket 33 pivotally movable about the pivot post 31 through the agency of an eccentric screw 34 having a head disposed in a slot 36 of the bracket 33. The bracket is held in

adjusted position about the post by a clamping screw 37 passing through arcuate slot and threaded in the plate 32. The plate 32 is centrally apertured at 38 to allow the passage of the cam 27.

The lever 30 is insulated from the post 31 by an insulating bushing 39. The lever 30 carries a contact 41 for cooperation with a fixed contact 42 on the bracket 33, the rubbing block 29 cooperating with the lobes 28 of cam 27 for actuating the lever 30. A leaf spring 43 attached to the lever 30 urges the lever 30, as viewed in Fig. 1, in a counterclockwise direction to cause the contacts 41, 42 to be normally engaged and to resist separation of the contacts when the lobes 28 of the cam engage the rubbing block 29. A screw 45 secures a bracket 46 attached to a case 47 of a condenser to the plate 32. One foil of the condenser is grounded on the case and the other foil is connected by a wire 48 with the fixed end of the leaf spring 43. A wire 49 has one end connected to the spring 43 and has the other end connected to a terminal 50 insulatingly supported from the housing 20.

The circuit breaker mounting plate 32 is supported for rotation coaxially with the axis of the cam 27 by three

antifriction material bearings 55 which are not deleteriously effected by oil or engine operating temperatures. This material embraces a wide range of conventional bearing materials, for example various bronzes, porous metals such as; bronze with or without graphite, leaded bronzes, iron, iron-lead, iron-copper, copper-nickel etc. or the members may be formed from suitable plastics such as; Bakelite (phenol formaldehyde condensation products), Bakelite with graphite, other phenolic resins; molded nylon or any other thermo setting or thermoplastic materials having the same general characteristics of suitability. In other words, we do not wish to be limited to any one class of materials since any satisfactory antifriction composition will provide equivalent results.

The plate 32 shown in Figs. 1 and 2 is provided with two relatively rigid ears or shoes 56 and 57 integral with the plate 32 and a relatively thin resilient ear or shoe 58 attached to the plate 32 by a tubular rivet 59. Referring to Fig. 3, the resilient shoe 58 has a base 60 provided with a notch 61 which straddles a boss 62 extended from the normal plane of the plate 32. The rivet 59 and the boss 62 fixes the location of the shoe 58 with respect to the plate 32. It is pointed out that while the shoes 56 and 57 are integral with the plate 32 as shown, in Fig. 2, they may be attached to the plate by rivets or spot welding for example. Since the shoes 56, 57 and the resilient ear 58 are of similar configuration only the resilient ear which is thinner, will be referred to here in describing further detail construction of the ears. Each ear comprises segmental upwardly arcuately bent portion 63 terminating in flat angle flanges 64 for resting on the upper surface of bearing member 55.

The bearing members 55 are in this instance preferably molded in segmental form as shown in Figs. 1 through 5. Each bearing member 55 has an inner concave-convex portion 65 concentric with the axis of the shaft 26. The bearing members are also provided with plain convex portion 66 for bearing against the cylindrical wall 21 of the housing 20 and each bearing has a depending lug 67 for bearing against the surface 21 below the opening to prevent the bearing member from tilting relative to the surface 21. The plane convex portion of each bearing has a cylindrical portion or shank 68 to fit into one of the openings. The openings 23, 24 and 25 in this instance are counterbored to provide shoulders 69. The shanks 68 are provided with a recess to provide thin wall portions 68' the outer peripheries of which wall are provided with spaced bosses 70. Thus, when the shank 68 of the bearing 55 is forced into the opening the thin wall portion 68' will contact slightly to permit the bosses 70 to be forced into the openings. After the bosses 70 pass the shoulder 69 the thin wall will tend to expand toward its normal state with the bosses 70 projecting behind the shoulders 69 to hold securely the shanks 68 in the openings in the housing, and cause the near plain concave surfaces to bear against the surface 21 of the housing 20.

The procedure of assembling the plate 32 within the housing with the three bearings in place is as follows: The plate 32 is moved axially to cause the resilient ear to be sprung inwardly until the flanges 64 of the respective shoes engage the upper surfaces of their respective bearing member 55. The flanges 64 are prevented from passing below the upper surfaces of the bearing member due to the fact that the periphery of the plate 32 will engage the shoulder 22 of the housing before the edges of the flanges 64 pass the shoulder of the convex surfaces 65 of the bearing members 55. After the insertion of the plate between the bearing members the resistance of the metal of which the shoe 58 is made holds the plate in position so that a minimum amount of horizontal play exists, thus the plate 32 is properly supported for oscillatory movement when same is moved by a suction device 71. While the bearing surfaces present very smooth convex surfaces and which are contacted by the shoes of the breaker plate 32, the frictional resistance between the

ears and bearing members can be further reduced by greasing the bearing surfaces. By greasing the surfaces there is substantially no interferences with the oscillatory movement of the plate 32.

It will be noted that the spring shoe 58 is located substantially 180° from the location of the cam operating force of the circuit breaker. This is important in order to prevent the plate 32 from tilting when the cam lobes 28 engage the rubbing block 29. The resilient shoe 58 prevents the reaction of the cam 27 upon the rubbing block 29 when the block 29 strikes the lobes 28 of the cam. The force is such that the plate 32 has the tendency to rock on the bearings 55 and lift the shoes from their bearings. This is prevented by the tension of the resilient shoe 58. The tension of the shoe 58 is sufficient to remain in contact with its bearing, thus rocking of the plate is prevented and the angularity of the plate relative to the cam is maintained.

A suction device 71 is provided to effect ignition timing in accordance with the load of the engine. The suction device 71 for rotatably adjusting the plate 32 to advance or retard the ignition forms no part of the present invention, however there is shown a suction device comprising shells 72 and 73 which are secured at their peripheries with the peripheral edge of the diaphragm 75 therebetween. The central portion of the diaphragm is connected with one end of a link or arm 76 which operates through a slot in the wall 21 of the housing 20. The other end of the link is pivotally connected with the tubular rivet 59 attached to the plate 32. A stop member 77 fits over the rivet and holds the link in place. The stop member 77 is held in position by a screw 78 which passes through the cap and has threaded engagement with the tubular bushing 59.

Figs. 6, 7 and 8 show modified forms of the mounting circuit breaker plate and the anti-friction bearings. The parts of the modified forms have been given the same numbers as the numbers of the first form but with the suffices "a," "b," "c," and "d." By this similarity of the parts of the modified forms, the part of the first form will be apparent. Therefore no description will be given to similarity of construction. The following difference in construction of the plate 32 and the bearing members is now set forth.

In Fig. 8, the second modified form of the invention, the circuit breaker plate 32a has separately applied shoes 56a and 57a attached to the plate 32a by two rivets 80 only one of which is shown. The resilient shoe 58a is fixed to the plate 32 by tubular rivet 59a. The shoes have a base 60a provided with a notch 61a which straddles a boss 62a on the plate 32a. By this arrangement the shoe 58a is prevented from turning on the plate 32a. In this modified form of the invention it is pointed out that each shoe has an arcuate upwardly bent portion terminating in a doubly curved portion 81 and portion 82 to provide grooves 83 to partially receive an arcuate conical head 55a made of an antifriction material and each bearing has a straight shank 68a which is fitted into one of the openings provided in the cylindrical wall 21 of the housing 20. In this construction the portions 81 and 82 respectively have line contact with the upper and lower surfaces of the conical head. The line contact of the portion 82 is clearly shown in Fig. 9. Fig. 10 shows a slightly modified construction of the shoes. In this instance the shoes are spherical in shape, see Fig. 11 so as to make point contact with the bearing. If desired the shank may be provided with a slot 84 which will contract as the shank is urged into the opening and then tend to expand toward its normal state to grip the wall of the opening to securely hold the shank 68a in said opening.

Fig. 12 shows a third modified form of the invention. In this instance the circuit breaker mounting 32b has a pair of integral shoes 56b and 57b, only the shoe 56b is shown. The resilient shoe 58b is attached to the

plate 32b by a tubular rivet 59b. The resilient shoe 58b has a base 60b provided with a notch 61b which straddles a boss 62b on the plate 32b which prevents the resilient shoe from turning relative to the plate 32b. In this third form of the invention each shoe 56b, 57b and resilient shoe 58b has an upwardly bent portion terminating in a doubly curved portion 35 to provide shallow grooves 36 to receive partially a conical head 55b of an antifriction bearing 55b. Each bearing has a shank 68b which is fitted in an opening provided by the cylindrical wall 21 of the housing 20.

When the plate 32b is assembled within the housing 20 with the bearing member 55b in place, the plate is moved axially to cause the resilient ears of shoe 58b to be sprung inwardly until the grooves 36 snap over the heads 55b. After the plate 32 is so positioned the link is connected with the rivet and held in position by a stop member 88. The stop member is attached to the rivet by a screw 87 having threaded engagement with the tubular rivet 59b. It is pointed out that the stop member is placed adjacent the resilient ear 58b to prevent accidental displacement of the plate 32b.

Fig. 13 shows a fourth modified form of the invention wherein antifriction metallic bearings are used instead of bearings made of molded plastic. It is pointed out that either form of circuit breaker plate heretofore described may be used with the metallic bearings so long as the bearing heads are formed to fit the respective grooves in the arms. In the form shown in Fig. 13 the shoes or ears 56c and 57c are integrally formed with the plate 32c. The resilient ear 58c is attached to the plate 32c by a tubular rivet 59c and held against turning by providing the base with a notch 61c which straddles the boss 62c. In using the bearing members the shank 68c is staked to the housing wall 21 as indicated at 90.

Fig. 15 shows a fourth modified form of the invention. In this instance the circuit breaker plate is provided with integral ears 56d and 57d and a resilient ear 58d. These ears are much wider than the bearing members and each ear has an upwardly bent portion terminating in an angular curved portion to provide elongated grooves to receive spherical heads 55d of antifriction bearing material and each bearing has a shank to fit in a respective opening in the housing wall 20 of the housing.

Fig. 17 is a view showing a doubly curved type of curvature which may be formed on the shoes and the bearings whereby the shoes will smoothly and freely slide over the bearing members. For example Fig. 17 illustrates how the shoes 56, 57 and 58 associated with the plate 32 could have its upwardly bent portion, which forms the shoes, terminate in a doubly curved arcuate groove whose curvature is the same as the inner arcuate surface of the bearing so that the grooves of the shoe will have full surface engagement with the bearing as shown in Fig. 17.

Fig. 18 shows a construction of a bearing having two radial shanks for fitting engagement with a pair of openings formed in the cylindrical wall 20 of the housing.

While the embodiments of the present invention constitute a preferred form, it is to be understood that other forms might be adopted.

What is claimed is as follows:

1. A distributor comprising in combination, two members rotatable relative to one another consisting of a body and a breaker plate positioned therein, a plurality of stationary molded nylon antifriction bearings disposed between said members and fixedly assembled to one of said members, and a grooved bearing surface adapted to slide on said bearings, said surface being carried by the other of said members, whereby the breaker plate is rotatable relative to the body on said bearings.

2. A distributor comprising in combination, a housing having a generally circular inner wall; a plurality of sta-

tionary circumferentially spaced antifriction bearing elements fixedly assembled in spaced apertures through the housing and extending inwardly from said wall of said housing; a circuit breaker plate mounted within the housing; a plurality of spaced ears associated with the plate said ears having an overall diameter less than the inner diameter of said housing, each of said ears having a groove formed to at least partially fit around and slide on the elements whereby the plate is freely rotatable with respect to the housing without wobble.

3. A distributor in accordance with claim 2 wherein the antifriction bearings are metallic.

4. A distributor in accordance with claim 2 wherein the antifriction bearings are non-metallic.

5. A distributor comprising in combination; a housing having a generally circular inner wall; a plurality of stationary circumferentially spaced elongated antifriction bearing elements having a curvature similar to the curvature of said housing wall fixedly assembled thereto and extending inwardly therefrom; a circuit breaker plate mounted within the housing; a plurality of spaced ears associated with the plate, each of said ears having a groove formed to at least partially fit around and slide on its respective element whereby the plate is freely rotatable with respect to the housing without wobble the outer diameter of said ears being less than the inner diameter of said housing.

6. A distributor comprising, a housing having a cylindrical inner wall; a plurality of circumferentially spaced, non-metallic anti-friction bearing members anchored to said wall, said bearing members having inner convex bearing surfaces coaxial with the axis of the inner wall of the housing; a circuit breaker mounting plate located within the housing; a plurality of shoes equal in number to the bearing members and associated with said plate, said shoes being shaped to provide upwardly converging portions to engage the lower side of the convex surfaces of the bearing members to resist upward axial movement of the plate relative to the housing and having integral angle portions extending outwardly from the ends of the converging portion to slide on the top of the bearing to support the plate at right angles to the axis of the housing at least one of the shoes being resilient to provide for facile rotation of the plate relative to the housing and also to prevent wobbling of plate.

7. A distributor comprising in combination, a housing; a plurality of spaced molded nylon bearing elements, each of said elements having extension means thereon fitting in an opening in said housing to form an anchor for said element; a circuit breaker plate mounted in said housing; a plurality of spaced ears carried by said plate, each of said ears having a groove to receive one of the elements and slide along said element whereby the plate is freely rotatable with respect to said housing.

8. A distributor comprising in combination, a housing, a plurality of stationary circumferentially spaced molded nylon bearing elements fixedly assembled in spaced apertures through said housing, a circuit breaker plate mounted within said housing, a plurality of spaced ears associated with the plate, each of said ears having a groove formed to at least partially fit around and slide on the elements whereby the plate is freely rotatable with respect to the housing without wobble.
